DESIGN FOR A COOKING TOP FOR GAS
COOKSTOVES

Herbert M. Reeves, Kankakee, Ill., assignor to
Florence Stove Company, Gardner, Mass., a
corporation of Massachusetts

Application April 11, 1947, Serial No. 138,322

Term of patent 7 years

(Cl. D81—25)

To all whom it may concern:

Be it known that I, Herbert M. Reeves, a citizen of the United States, residing at Kankakee, in the county of Kankakee and State of Illinois, have invented a new, original, and ornamental Design for a Cooking Top for Gas Cookstoves, of which the following is a specification, reference being had to the accompanying drawing forming a part thereof.

Figure 1 is a perspective view of a cooking top for gas cookstoves, showing my new design.

Figure 2 is a transverse sectional view taken approximately in the plane of line 2—2 of Fig. 1.

I claim:

The ornamental design for a cooking top for gas cookstoves, substantially as shown.

HERBERT M. REEVES.
